UNITED STATES PATENT OFFICE.

JAMES WILLIAM PARKER, OF HARROW, ENGLAND.

AUTOMOBILE GAS PRODUCER.

Application filed August 29, 1921. Serial No. 496,663.

(GRANTED UNDER THE PROVISIONS OF THE ACT OF MARCH 3, 1921, 41 STAT. L., 1313.)

To all whom it may concern:

Be it known that I, JAMES WILLIAM PARKER, a subject of the King of Great Britain, and a resident of Harrow, England, 5 have invented certain new and useful Improvements in Automobile Gas Producers (for which I have filed an application in Great Britain, May 3, 1918, Patent No. 126,140), of which the following is a specification.

This invention relates to the generation of gas for use as fuel in internal combustion engines, more particularly such as are employed in the propulsion of automobile 15 vehicles, motor boats, and the like, by passing air and steam through an incandescent mass of carbonaceous material such as for example coke or coal in a gas producer surmounted by a feed hopper from which the 20 fuel is fed by gravity, the air and water being warmed by the heat generated, and the gas being drawn off from the hottest part of the mass of fuel.

In such apparatus it has been proposed 25 to arrange a water heater at the base of the producer, and it has also been proposed to arrange in the body of the carbonaceous material a heater in the form of a rotary tube provided with jet outlets.

According to this invention a boiler is 30 located in the base of the producer and is mounted in or near the fire-grate and has at its upper end a nozzle or opening for the escape of steam into the mass of incandescent fuel, the boiler projecting into the fuel a sufficient distance to be properly heated, and being fed from beneath by 35 gravity with water from a vessel, wherein the water level is maintained constant by 40 means of a float valve or other device serving to control the supply to the vessel by gravity from a supply tank.

The mass of carbonaceous material within 45 the fire-box is replenished automatically by gravity from a hopper, and the air, before its introduction into the mass of carbonaceous material, is preferably warmed by being caused to pass through a jacket space surrounding or in contact with the 50 wall of the fire-box; whilst the fuel gas is preferably caused to leave the hottest part of the incandescent mass in a general upward direction.

In the accompanying drawings Fig. 1 is

a vertical section of one form of producer 55 made in accordance with this invention. Fig. 2 is a vertical section showing a modified construction. Figure 3 is an enlarged vertical sectional view of the supply vessel and lower portion of the chamber.

In the apparatus shown in Figure 1 the fire-box consists of a vertical cylindrical chamber *a* formed of or lined with fire-clay, surmounted by a feed-hopper *b* for the solid fuel which, as it gradually burns away 60 within the fire-box, descends by gravity into the latter. The fire-box is surrounded by a jacket space *c* to which air is admitted at its bottom as at *d'* and from which the air, warmed by contact with the inner wall of 65 the jacket, enters the fire-box through holes *e* at the upper end so as to pass thence downwards through the solid fuel from above the level where the mass of fuel is kept in a state of incandescence. The bottom of the 70 fire-box *a* is furnished with a fire-grate *f* upon which the solid fuel rests and which surmounts a space closed by a removable ash-pan *g*; a fire-door through which the 75 fire can be lighted, being provided at the lower part of the fire-box wall to facilitate the periodical clearing out of the ashes.

In the centre of the fire-grate is mounted a small boiler *h* having at its upper end a nozzle or opening *i* for the escape of steam 80 into the mass of incandescent fuel which rests upon the grate *f* and into which the boiler *h* projects a sufficient distance to insure its being heated to the requisite temperature: this boiler *h* is fed from beneath 85 by gravity with water by a pipe *j* from a vessel *k* wherein the water level is maintained constant by means of a float valve or other device serving to control the supply to the vessel by gravity from a supply 90 tank.

The mass of solid fuel within the fire-box is kept in a state of incandescence for some distance from the fire-grate upwards, and from a level corresponding substantially with the hottest point, a gas delivery pipe *o* leads centrally upwards through the mass of fuel and out through the wall of the fire-box *a* at or near the top of the latter.

The hopper *b* may be closed at its top, and furnished with a movable internal door *b'* for temporarily supporting the mass of

fuel within the hopper when the fire-door is opened to enable the fire-box to be cleared out.

In the form of apparatus shown in Figure 5 2 the fire-box consists of an upright tube of J-shape formed of or lined with fireclay, the longer limb a' of the tube being surrounded by the feed-hopper b whilst the gas delivery pipe σ leads from the top of 10 the shorter limb a^2 ; a grid p is interposed between the summit-level of the solid fuel in this shorter limb a^2 of the tube and a gas collecting space q immediately beneath the inlet of the gas delivery pipe σ ; whilst a 15 small boiler h , fed with water as in the previously described construction from a vessel h , is mounted within the lower part of the bend of the J tube above a recess or chamber r projecting beneath the bend 20 and serving as an ash-pan.

The air, which may be caused initially to circulate through a jacket enclosing the J tube but not shown, is admitted by the pipe d' to the upper end of the longer limb 25 a' of the latter, and the mass of solid material within the tube is kept in a state of incandescence from the upper end of the shorter limb a^2 to a point about half way up in the height of the longer limb a' . The 30 curvature of the bend, and length of the shorter limb of the J tube, should be such as to insure that this limb a^2 is kept filled with fuel owing to the pressure exerted by the mass of material descending gradually 35 in the longer limb a' , and that the temperature of the mass of incandescent material at its summit-level within the shorter limb shall be maintained substantially equal to the maximum temperature within the

fire-box. As is obvious from the first paragraph of the specification, a mixture of air and steam is used to generate the gas, the air being admitted through d' passing to the top of the jacket and entering the fire box through the holes e and passing downwardly through the fuel mingling with the steam passing off from the boiler h .

A fire-door may be provided near the lower part of the bend, preferably in the shorter limb.

In Figure 3 a supply vessel k is shown as containing a float 2 provided with a valve 3 for controlling the inlet of water from a source of supply through the pipe 4. The float valve maintains a constant level of 55 liquid in the vessel k in accordance with the well known principle. Devices of this kind are largely used in carburetors for internal combustion engines.

What I claim is:—

An automobile gas producer having combined therewith a small boiler located in the base of the producer and mounted near the fire-grate, having at its upper end an opening for the escape of steam into the 65 mass of incandescent fuel, the boiler projecting into the fuel a sufficient distance to be properly heated, and being fed from beneath by gravity with water from a vessel 70 wherein the water level is maintained constant by means of a float valve serving to control the supply to said vessel by gravity from a supply tank, and means for delivering the gas generated from the hottest zone of the incandescent fuel within the generator.

In testimony whereof I affix my signature.
JAMES WILLIAM PARKER.
